UNITED STATES PATENT OFFICE.

HENRY J. SAGE, OF ROCHESTER, PENNSYLVANIA.

ELECTRIC-ARC LAMP.

SPECIFICATION forming part of Letters Patent No. 599,635, dated February 22, 1898.

Application filed March 19, 1897. Serial No. 628,338. (No model.)

To all whom it may concern:

Be it known that I, HENRY J. SAGE, a citizen of the United States, residing at Rochester, in the county of Beaver and State of Pennsylvania, have invented or discovered a new and useful Improvement in Arc-Lamps, of which the following is a full, clear, and exact description, reference being had to the accompanying drawings, forming part of this application, in which—

Figure 1 is a vertical section of the complete lamp except the chimney for the positive-carbon rod, which is broken off immediately above the frame. Fig. 2 is a sectional detail view through the lower-carbon socket. Fig. 3 is a cross-section on the line III III of Fig. 1.

This invention relates to electric-arc lamps, the object being to produce a lamp which shall be simple in construction and adapted 20 to incandescent circuits.

It is also the object of the invention to produce a simple method of prolonging the life of the carbons.

Referring to the drawings, A is part of the 25 casing which protects the frame B, which forms the main support of the mechanism.

b' is the base of the frame, made circular in form.

C is the electromagnet, the winding of which 30 is in the series circuit of the lamp. The plunger c', with the cross-piece c², forms the armature of the magnet. By means of the links a⁴ the clutch D is connected to the armature of the magnet. This clutch consists of two 35 jaws a', pivoted to the levers a³, which grip the carbon-feed rod E. The levers a³ are pivoted to the guide a² at a⁵, and the links a⁴ are pivoted to the levers a³, as indicated.

The carbon-feed rod E has its bearings in 40 the frame B, passes through the guide a² and jaws a' of the clutch D, and at its lower end carries the positive-carbon holder F.

K is one of two dash-pots. K' is the link, 45 pivoted at its lower end to the cross-piece c² of the armature, and at the upper end of the link is attached the plunger of the dash-pot. The second dash-pot is behind the one shown in the drawings, and between the two the carbon-feed rod E passes.

50 HH are the side rods of the lamp, plugged at one end to prevent the passage of air through them.

H' is the support for the lower or negative carbon holder F', which has a threaded extension f, which receives the globe-holder T, as 55 indicated.

G is the glass arc-inclosing globe, open at both ends, the lower end having a screw-shell g', cemented or mechanically attached to it, so that the globe may be securely screwed 60 into its seat in the lower-carbon holder F', as indicated. The upper opening g of the arc-inclosing globe G is just large enough to permit the upper carbon to slide freely through it. In practice I have found that for a carbon one-half inch in diameter an aperture nine-sixteenths of an inch in diameter will give good results.

M is the casing of the lamp, flanged at the top, to which the pliable washer m² is attached, and n' n' are clips through which the screws S' are tapped for holding the outer globe S in position against the washer m².

m' is a pliable washer firmly attached to the base b' of the frame B.

m³ is a pliable washer in the outer-globe holder T.

The seat of the arc-inclosing globe G in the lower-carbon holder F' also contains a pliable washer g², against which the screw-shell g' firmly bears. The clips n² are firmly attached to the casing M and have holes in them through which the side rods freely pass. On unscrewing the globe-holder T from the lower-carbon holder F the outer globe S, together 85 with the casing M, may be lowered until the clips n² strike the support H', and the casing M and globe S will rest suspended by the clips, thus giving ready access to the lamp for trimming. When the globe S and casing M are 90 raised and the globe-holder T screwed tightly into place, the joints between the globe S and holder T, the globe S and casing M, and the casing M and frame B, by reason of the pliable washers m' m² m³, will be practically air-tight, and consequently air will be excluded 95 from the interior of the lamp.

The arc-inclosing globe being mechanically air-tight at the bottom and having only a small opening at the top there will be no circulation of air.

When the lamp is burning, the heat due to the arc will expand the gas in the arc-inclosing globe, and to equalize the pressure with

the outer air the gases will escape through the small upper opening g in the arc-inclosing globe around the upper carbon. There will be little tendency for air from the outer chamber to enter the arc-inclosing globe, thereby prolonging the life of the carbons because of the exclusion of air from the arc.

I have found that with a twelve-inch upper carbon and a six-inch lower carbon half-inch 10 in diameter the lamp will burn for one hundred and fifty hours or over.

The operation of the mechanism is as follows: The current enters the lamp at the positive binding-post, passes through the 15 windings of the magnet C, thence to the frame B, and through the bearings to the rod E, through the upper and lower carbons, thence through wire up side rod to the negative binding-post. When the lamp is not in operation, the carbons touch each other, as indicated in the drawings. When the current is turned on, it passes through the magnet-spools, thus energizing the magnets, and these, as stated, through the frame, carbon-feed rod, and carbons, and finally out at the 20 negative binding-post. The magnet being energized the plungers c' , with cross-piece c^2 , are drawn up into the magnet-spools. This motion raises the links a^4 , which draw the 25 long arm of the levers a^3 upward and the short arms together, forcing the jaws a' inward, thereby causing such jaws to come in contact with the carbon-feed rod and clutch it. Any further upward movement of the armature 30 of the magnet will lift the clutch, feed-rod, and upper carbon, and thus an arc will be struck. As the armature further lifts the clutch and carbon rod the length of the arc will be increased, the resistance of the arc 35 will increase, and therefore the current flowing in the magnet-spools and through the carbons will be diminished, which decrease of current will decrease the strength of the magnet. The strength of the magnet, by the upward movement of the armature with the 40 clutch and carbon-rod, will be decreased to the point where the strength of the upward pull of the magnet will be balanced by the weight of the combined armature, clutch, 45 feed-rod, &c. As the carbons further burn away, the arc will be increased and the strength of the magnets decreased. Consequently the armature, with clutch and feed-rod, will drop, thus shortening the arc and 50 thereby increasing the strength of the magnet. A new balance between the strength of the magnets and weight of the mechanism will be established, and this cycle will be 55 repeated as the carbons burn away, the clutch 60 constantly dropping lower and lower. Finally the guide a^2 of the clutch will rest on its seat on the frame, as indicated in the drawings, and any further downward movement on the 65 part of the armature will throw the levers a^3 down and outward, the pressure of the jaws a' on the carbon-feed rod E will be relieved, and the rod E will slip through the clutch,

thus shortening the arc again. This action will increase the strength of the magnet, the armature will be raised, the clutch will grip 70 the carbon-rod, and a new balance will be established. The above actions will be repeated until finally the carbon-holder F rests on the arc-inclosing globe G. The carbons cannot further descend, and as they are consumed the arc will lengthen and finally break 75 and the light will be extinguished.

Changes and modifications may be made in the construction and arrangement of the parts, and I do not wish to limit myself to 80 the exact form and construction illustrated. A single solenoid-magnet with spool and armature concentric with the feed-rod may be employed with good results. The clutch-jaws may be sufficiently wide, so as to grip a 85 ribbon, chain, cord, or flexible carbon-support.

The arc-inclosing globe may be clamped to the lower-carbon holder instead of screwed, as shown, and, if desired, the outer globe may be of such a design as to bear directly against 90 the pliable gasket m' ; also, the magnets may be differential or shunt instead of in series, as described.

What I claim is—

1. The combination, in an arc-lamp, of a 95 carbon-socket supported by rods from the base of the lamp provided with a threaded extension, a cushioned seat in the upper end of the socket surrounding the carbon and a bulbous globe G supported in the seat extending 100 above the arc and contracted closely around the upper carbon with a narrow annular intervening space g between the carbon and the inwardly-turned edge of the globe, substantially as set forth.

2. In combination with an arc-lamp provided with a carbon-socket supported by rods from the base of the lamp and a threaded lower extension; an inclosing casing below the base, a globe below the casing, a globe-holder supporting the globe screwed upon the threaded extension, and packing-rings between the globe-holder and globe, between the globe and casing and between the casing and base, respectively, substantially as set 105 forth.

3. In combination with an arc-lamp provided with a carbon-socket supported by rods from the base of the lamp and a threaded lower extension; an inclosing casing below 110 the base provided with clips embracing the rods, a globe, and a globe-holder screwed upon the threaded extension, substantially as set forth.

4. The combination, in an arc-lamp, of a 115 carbon-socket supported by rods from the base of the lamp provided with a threaded extension and a cushioned seat in the upper end of the socket surrounding the carbon, a bulbous globe supported in the seat extending 120 above the arc and contracted closely around the upper carbon, an inclosing casing below 125 the base, a globe below the casing, a globe-holder supporting the globe screwed upon 130

the threaded extension, and intervening packing-rings, substantially as set forth.

5. In an arc-lamp, an arc-inclosing globe surrounding the arc provided with a base secured with an air-tight joint in the base of the lower-carbon holder and contracted at the top to an approximately close fit around the upper carbon, with a surrounding outer glass globe suspended from the case of the lamp,

the globe and the outer casing forming an air-tight inclosure for the arc-inclosing globe, substantially as set forth.

In testimony whereof I have hereunto set my hand this 18th day of January, 1897.

HENRY J. SAGE.
